(57) **CLAIM**

The ornamental design for a “key chain dental floss dispenser”, as shown and described.

DESCRIPTION

FIG. 1 is a bottom plan view of the open key chain dental floss dispenser,

FIG. 2 is a right side elevational view of the open key chain dental floss dispenser,

FIG. 3 is a top plan view of the open key chain dental floss dispenser,

FIG. 4 is a rear end elevational view of the open key chain dental floss dispenser,

FIG. 5 is a front end elevational view of the open key chain dental floss dispenser,

FIG. 6 is a left side elevational view of the open key chain dental floss dispenser,

FIG. 7 is a perspective view of the closed key chain dental floss dispenser,

FIG. 8 is a top plan of the closed key chain dental floss dispenser; and,

FIG. 9 is a side elevational view of the closed key chain dental floss dispenser.

The broken lines showing a key ring in FIGS. 7, 8 and 9 are for illustrative purposes only and do not form part of the claimed design.
